HANGER APPARATUS

Bror Hillberg, Chicago, Ill., assignor, by mesne assignments, to Reconstruction Finance Corporation, Chicago, Ill., a corporation of the United States

Application January 10, 1938, Serial No. 184,200

6 Claims. (Cl. 25—131.5)

The present invention relates generally to hanger apparatus for use in suspending from a horizontally extending I-beam or like structural element a form for use in the formation of a concrete beam for fireproofing purposes around the I-beam. More particularly the invention relates to that type of hanger apparatus which is especially designed for use with a form embodying an elongated board-formed bottom with a series of laterally spaced transversely extending wooden cleats on the underside thereof and a pair of elongated board-formed side members at, and extending upwardly from, the side edges of the bottom member, and comprises a series of wire formed cleat encircling straps which are adapted upon raising or hoisting of the cleat equipped bottom member into place beneath the I-beam and before mounting of the side members to be attached to the I-beam and serve upon attachment to the I-beam and after mounting of the side members to hold the form in place during pouring and setting of the concrete in connection with formation of the fireproofing beam around the I-beam.

One object of the invention is to provide a hanger apparatus of this type which is an improvement upon, and may be applied more readily than, previously designed apparatus of the same general character and is characterized by the fact that the wire formed cleat encircling straps are adapted to be applied to the cleat ends prior to raising or hoisting of the bottom member and are of such design and construction that after raising of the bottom member into place beneath the I-beam they may be manipulated into connected relation with the beam by the operator from a point or position above the beam.

Another object of the invention is to provide a hanger apparatus of the type under consideration in which the straps are adapted to be used in pairs corresponding in number to the cleats under the bottom member of the form and are so shaped and constructed that they serve efficiently and effectively when in their operative position to hold the bottom member of the form at a predetermined or fixed distance beneath the bottom flange of the I-beam.

A further object of the invention is to provide a hanger apparatus of the last mentioned character in which each of the straps consists of a U-shaped wire which is adapted to form a sling for and extend upwardly from the cleat to which it is applied, and has the upper ends thereof bent at substantially right angles and provided with a heavy wire downwardly facing hook for attach-

ment to one of the side margins of the top flange of the I-beam.

A still further object of the invention is to provide a hanger apparatus of the type and character under consideration which may be fabricated or manufactured at a low and reasonable cost and is generally of novel and improved construction.

Other objects of the invention and the various advantages and characteristics of the present hanger apparatus will be apparent from a consideration of the following detailed description.

The invention consists in the several novel features which are hereinafter set forth and are more particularly defined by claims at the conclusion hereof.

In the drawings which accompany and form a part of this specification or disclosure and in which like numerals of reference denote corresponding parts throughout the several views:

Figure 1 is a perspective view showing a hanger apparatus embodying the invention in connection with an I-beam and the cleat equipped bottom member of a form for use in the formation of a concrete fireproofing around the I-beam, and illustrating the manner in which the straps which constitute the apparatus are adapted to be applied or connected to the top flange of the I-beam;

Figure 2 is a perspective view illustrating the manner in which the wire formed straps are applied to the ends of the cleats on the underside of the bottom member of the form prior to raising or hoisting of such member into place beneath the bottom flange of the I-beam;

Figure 3 is a vertical transverse sectional view showing the cleat equipped bottom member of the form in raised or hoisted relation with the bottom flange of the I-beam and the upper hook equipped ends of a pair of straps of the apparatus positioned over the top flange of the I-beam in readiness for connection to the same;

Figure 4 is a similar sectional view showing the bottom member of the form lowered a slight distance from the bottom flange of the I-beam and the hooks of the two straps in hooked or connected relation with the side margins of the top flange of the beam;

Figure 5 is a vertical transverse sectional view showing the straps in their form suspending or supporting position and after straightening of the lower bends in the intermediate portions of the strap forming U-shaped wires;

Figure 6 is a vertical transverse sectional view showing the hanger apparatus in its operative

position and with the form filled with concrete; Figure 7 is a detail perspective view of a sheet metal bearing forming saddle which with like saddles may be applied to the lower ends of the 5 U-shaped strap-forming wires to prevent the intermediate or connecting pieces of such wires from cutting into the bottom faces of the cleats; and

Figures 8 and 9 are front and side views, 10 respectively, of one of the spacers which are used with the apparatus.

The hanger apparatus which is shown in the drawings constitutes the preferred embodiment of the invention. It is adapted for use in suspending or supporting a form F around a horizontally extending I-beam I in connection with the formation of a concrete fireproofing B around the I-beam and comprises a series of pairs of straps 8 and 9, 10 and 11, and 12 and 13. The I-beam I comprises a vertically extending web i, a top flange i¹ and a bottom flange i². These two flanges are respectively formed integrally with the top and bottom margins of the web and project horizontally from both of the side faces of the web. The form F is of conventional or standard design for the purpose for which it is adapted and consists of a bottom member f with a series of wooden cleats f¹ on the underside thereof, and a pair of board-formed side members f². The bottom member f is in the form of a board and is adapted, as hereinafter described, to be suspended by the hanger apparatus at a fixed distance beneath the bottom flange i² of the I-beam I. The cleats f¹ extend transversely of the bottom member of the form and are spaced equidistantly apart, as shown in Figure 1. They are nailed or otherwise suitably fixed to the bottom or underside of the bottom member f, and are of such length and so arranged that the ends thereof project beyond the side edges of said bottom member. The side members f² of the form are adapted after suspension of the cleat equipped bottom member from the I-beam by the hanger apparatus, to be placed on the ends of the cleats in an upstanding position against the side edges of the bottom member f and to be suitably maintained in fixed laterally spaced relation, as shown in Figure 6 of the drawings. After assembly of the form around the I-beam concrete is poured into it and permitted to set in order to form the fireproofing B around the I-beam as well understood in the art.

The strap 8 consists of a U-shaped wire 14 and 55 a wire hook 15, and is adapted to form a sling for one end of one of the form cleats f¹. It is preferably of seven (7) gauge stock and consists of a pair of side pieces 16, and a bottom piece 17 which extends between and serves laterally to 60 space the lower ends of the side pieces 16 and is adapted to underlie the cleat end to which the strap 8 is applied. The lower parts of the side pieces 16 are substantially straight and are upwardly convergent with the result that the lower ends thereof grip frictionally the sides of the aforesaid cleat end and serve as a result of their grip to hold the strap 8 against sidewise tilting when it is applied to its cleat end. The intermediate parts of the side pieces of the U-shaped 65 wire 14 extend upwardly and inwardly and are connected by bends 18 of approximately 45° to the upper ends of the lower parts of the side pieces. They are comparatively short and are adapted, after application or connection of the 70 strap 8 to the I-beam I to extend downwards

from the adjacent side edge of the top flange of such beam. The upper parts of the side piece 16 extend inwardly at substantially right angles to the lower parts of the side pieces and are connected by bends 19 of approximately 45° to the intermediate parts of the side pieces 16. They are adapted to overlie and rest upon the top flange i¹ of the I-beam when the strap 8 is in connected relation with the beam and with the exception of the end extremities thereof are 10 straight. The hook 15 faces downwardly and is preferably formed of zero (0) gauge stock. It serves to maintain the upper end of the wire 14 in hooked relation with the I-beam and consists of an elongated straight shank 20 and a downwardly extending inturned hook part 21. The shank is adapted to overlie and rest upon the top flange of the I-beam when the strap 8 is in its operative position and its inner end extends 15 between and is welded to the end extremities of the upper parts of the side pieces 16 of the U-shaped wire 14. The hook part 21 is adapted to extend around the top flange of the I-beam, as shown in Figures 4, 5 and 6, and its bend is such that when it is in its operative position it engages 20 the underface of the top flange of the I-beam. The bent intermediate parts of the side pieces 16 of the wire 14 permit the hook 15 to project over or beyond the adjacent side edge of the top flange of the I-beam prior to attachment of the 25 hook onto such edge of the top flange (see Figure 3). The length of the intermediate parts of the wire is such that the horizontal distance or space between the bends is slightly greater than the length of the space within the hook 30 part 21 of the hook 15. As a result of this, when the board-formed cleat equipped bottom member f is raised or hoisted in connection with attachment of the hanger apparatus to the I-beam I the hook 15 is free to extend beyond the adjacent 35 side edge of the top flange of the beam and in connection with lowering of the bottom member of the form can be swung or moved beyond the adjacent side edge of the top flange into proper 40 position for connection to the top flange. When the bottom member of the form is lowered the bent or angled intermediate parts engage the opposite side edge of the top flange of the I-beam and as the result of sliding downwards thereagainst, move or guide the upper parts of the 45 side pieces of the wire in such direction as to effect hooking of the hook 15 onto the top flange i¹. When the cleat equipped bottom member of the form is released for suspension by the hanger apparatus, the bends 18 will either straighten 50 as the result of the load upon the cross-piece 17 of the U-shaped wire 14 or may be straightened by striking them with a hammer, as shown by dotted lines in Figure 4. When the strap 8 is in its operative position with the form suspended 55 therefrom, the lower and intermediate parts of the side pieces of the U-shaped wire 14 are straight, as shown in Figure 5, and the upper parts of the side pieces and the shank 20 of the hook rest directly on the top face of the top 60 flange i¹ of the I-beam. The combined length of the upper parts of the side pieces 16 and the shank 20, that is, the distance from the bends 19 to the hook part 21 is equal to the width of the top flange and hence when the strap 8 is in place 65 the hook part 21 is in hooked relation with the adjoining side margins of the top flange and the bends 19 extend around the other or opposite side margin of said top flange. After straightening the bends 18, the bends 19 become substantially 70 75 80 85 90 95 100

right angle bends and prevent lateral displacement of the upper parts of the side pieces 16 and the hook 15.

The strap 9 is the same in design and construction as the strap 8 and is adapted to be applied to the other or opposite end of the cleat to which the strap 8 is applied. The upper parts of the side pieces of the U-shaped wire of the strap 9 and the hook of such strap are adapted, as shown in Figure 1, to extend in side by side relation with the top parts of the side pieces of the side pieces 16 of the strap 8 and the hook 15. They project, however, oppositely to the top parts and hook of the strap 8.

15 The straps 10 and 11 are the same in construction and design as the straps 8 and 9 and are adapted to be applied to opposite ends of another one of the cleats f^1 and the straps 12 and 13 are of similar design and are adapted to be applied to the ends of another one of these cleats, as shown in Figure 1.

In applying or using the hanger apparatus the hook equipped wire formed straps are first applied to the ends of the cleats f^1 prior to hoisting of the bottom member f of the form F. In applying the straps to the ends of the cleats the lower ends of the U-shaped wires are merely looped or slipped around the projecting ends of the cleats and are slid inwards until the lower ends of the lower parts of the side pieces of the wires are brought into abutment with the side edges of the bottom member f . When the straps are so applied or mounted they are left in a position wherein they extend upwardly and outwardly with sufficient space between the hooks to permit of movement of the hooks past the I-beam during hoisting of the cleat equipped bottom member under the beam. After connection of the straps to the ends of the cleats, the bottom member f of the form is hoisted upwards in any suitable manner until it practically engages the bottom flange of the I-beam. When in such position the straps are swung inwards in order to put the upper parts of the side pieces of the U-shaped wires and the hooks into overlapped relation with the top flange of the I-beam. After such swinging movement the bottom member f of the form is lowered and during such movement the hooks at the upper ends of the straps are brought into hooked or connected relation with the side margins of the top flange of the I-beam I. After this operation or step the bends between the intermediate and lower parts of the side pieces of the U-shaped wires of the straps are straightened by hammering them inwards. During the hammering operation the upper bends, that is, the bends between the intermediate and upper parts of the side pieces of the U-shaped wires of the straps are bent so that they are substantially right angle bends (see Figure 5). At the conclusion of the bend straightening operation, the operator by way of a hammer or like hammering tool, drives the portions of the lower parts of the side pieces of the U-shaped wires which engage or contact with the side edges of the bottom member f of the form into such edges so that the latter are straight from end to end. After proper attachment of the straps to the I-beam the side members f^2 of the form are mounted in place by placing them on the projecting ends of the cleats and moving them inwards into abutting relation with the side edges of the bottom member f . After suitably securing the side members of the form in place concrete is poured into the form

and permitted to set so as to form the concrete fireproofing beam B around the I-beam I. After setting of the concrete, the side members f^2 of the form F are removed. Thereafter the operator by way of a chisel or like tool severs the lower ends of the straps at the points where the lower parts of the side pieces of the U-shaped wires project beneath the bottom face of the fireproofing beam B. After such operation, the cleat equipped bottom member f of the form is freed upon the I-beam and suitably lowered out of contact with the fireproofing beam B.

In order to prevent side swaying of the form F after suspension of the latter from the beam by the improved hanger and also to assure proper spacing of the bottom member f of the form from the bottom flange f^2 of the I-beam pairs of C-shaped spacers 22 are provided. These spacers are suitably formed or bent from wire stock, preferably #4 gauge, and embody long horizontally extending bottom arms 23, short horizontally extending top arms 24, and vertically extending connecting parts 25. The connecting parts correspond in length to the desired or proper spacing between the bottom member f of the form and the bottom flange of the I-beam when said bottom member is held in its suspended position by the hanger apparatus. The bottom arms 23 have downwardly extending prongs 26 at their free ends and the latter are adapted to be driven into the bottom member f of the form so as to hold the spacers in an upright position with respect to said bottom member, as shown in Figure 2. The top arms 24 are approximately one-half as long as the bottom arms and have upwardly extending projections which are adapted when the spacers are turned at right angles, that is, into a transverse position with respect to the bottom member of the form F, as shown in Figure 6, to about 40 against the side edges of the bottom flange of the I-beam I. When the spacers are in their aforesaid transverse position the projections 27 prevent side swaying of the form F and the vertically extending connecting parts 25 show 45 proper spacing of the bottom member of the form from the bottom flange of the I-beam. The spacers 22 are adapted prior to hoisting of the cleat equipped bottom member of the form to be driven into connected relation with said bottom member in such manner that they extend parallel to the side edges of said member. After connection of the straps to the top flange of the I-beam and straightening the bends between the intermediate and lower parts of the side pieces 55 of the U-shaped wires of the straps the spacers are turned or rotated inwards by pliers or a like turning tool into their transverse position wherein they fit between and engage the bottom flange of the I-beam and the top face of said bottom member f . The right angle bends between the horizontally extending bottom arms 23 and the lower ends of the vertically extending connecting parts 25 are suitably weakened so that after removal of the bottom member of the form upon 60 setting of the fireproofing beam B such bottom arms may by striking with a hammer the prongs 26 be disconnected from the lower ends of the parts 25 of the spacers. The lower ends of the prongs are cut at an angle, as shown in Figure 8, 65 so that they are pointed and hence may be readily driven into the bottom member f of the form prior to raising or hoisting of such member under the I-beam I.

If the cleats f^1 of the form are formed of soft 75

wood and there is any likelihood of the bottom or connecting pieces of the U-shaped wires of the straps cutting or digging into the cleats and thus changing the desired spacing of the bottom member of the form with respect to the bottom flange of the I-beam each U-shaped wire may be provided with a sheet metal saddle 28, as shown in Figure 7. Such saddle is U-shaped for cleat receiving purposes and embodies outwardly extending flanges 29 at the ends thereof. Such flanges have apertures 30 on the central portions thereof for receiving the lower parts of the side pieces of the U-shaped wire of the strap with which the saddle is associated and the saddle, as shown in Figure 7, is adapted to be supported on and by the cross or bottom piece of such wire.

The herein described hanger apparatus may be manufactured at a low and reasonable cost for the reason that the straps are alike as far as design or construction is concerned and efficiently and effectively fulfills its intended purpose and may be readily applied. By fixing the combined length of the intermediate and lower parts of the side pieces of the U-shaped wires of the straps the apparatus may be made to support the bottom member of the form to which it is applied any desired distance from the bottom flange of the I-beam.

The invention is not to be understood as restricted to the details set forth, since these may be modified within the scope of the appended claims, without departing from the spirit and scope of the invention.

Having thus described the invention, what I claim as new and desire to secure by Letters Patent is:

1. A hanger apparatus for suspending from a horizontal structural element with a top flange a concrete form including a bottom member with a cross cleat secured thereto and having one end projecting therefrom, comprising a strap consisting of a U-shaped wire adapted to extend around and form a sling for the projecting end of the cleat and having the ends thereof bent laterally at substantially right angles and adapted upon raising of said bottom member under the element to be brought into overlying relation with the flange of the element, and a separate preformed downwardly facing substantially rigid hook having the shank parts thereof connected to the ends of said wire, said wire having the parts thereof immediately adjacent its ends extending at an acute angle with respect to said ends and adapted to permit the hook part of the hook to project beyond one side edge of the flange when said ends are in overlying relation with the flange and further adapted upon lowering of the strap with the cleat equipped bottom member to engage the other side edge of the flange and move said ends in such direction as to cause said hook part to grip said one side edge of the flange and connect the strap for suspension from the element.

2. A hanger apparatus for suspending from a horizontal structural element with a top flange a concrete form including a bottom member with a cross cleat secured thereto and having one end projecting therefrom, comprising a strap consisting of a U-shaped wire adapted to extend around and form a sling for the projecting end of the cleat and having the ends thereof bent laterally at substantially right angles and adapted upon raising of said bottom member under the element to be brought into overlying relation with the flange, and a separate preformed down-

wardly facing substantially rigid heavy wire hook having the shank thereof fitting between and welded to said ends of the wire, said wire having the parts thereof intermediate its ends extending at a substantially 45° angle with respect to said ends and adapted to permit the hook part of the hook to project beyond one side edge of the flange when said ends are in overlying relation with the flange and further adapted upon lowering of the strap with the cleat equipped bottom member to engage and slide upon the other side edge of the flange and move said ends in such direction as to cause the hook part to grip said one side edge of the flange and connect the strap for suspension from the element.

3. A hanger apparatus for suspending from a structural element with a top flange a concrete form including a bottom member with a cross cleat secured thereto and having one end projecting therefrom, comprising a strap consisting of a wire having a loop at one end thereof adapted to extend around and form a sling for the projecting end of the cleat and having its other end provided with a preformed downwardly facing hook and bent at substantially right angles so that it is adapted upon raising of said bottom member under the element to be brought into overlying relation with the flange, said wire also having an angled intermediate part adjoining said other end and adapted to permit the hook to project beyond one side edge of the flange when said other end is in overlying relation with the flange and further adapted upon lowering of the strap with the cleat equipped bottom member to engage and slide against the other side edge of the flange and move said other end in such direction as to cause the hook to grip said one side edge of the flange and connect said strap for suspension from the element.

4. A hanger apparatus for suspending from a structural element with a top flange a concrete form including a bottom member with a cross cleat secured thereto and having one end projecting therefrom, comprising a strap consisting of a U-shaped wire adapted to extend around and form a sling for the projecting end of the cleat and having the ends thereof provided with a preformed downwardly extending substantially rigid hook and bent at substantially right angles so that they are adapted upon raising of said bottom member under the element to be brought into overlying relation with the flange, said wire also having the parts thereof immediately adjacent its ends extending at substantially a 45° angle with respect to said ends and adapted to permit the hook to project beyond one side edge of the flange when said ends are in overlying relation with the flange and further adapted upon lowering of the strap with the cleat equipped bottom member to engage and ride on the other side edge of the flange and move said ends in such direction as to cause the hook to grip said one side edge of the flange and connect the strap for suspension from the element.

5. A hanger apparatus for suspending from a horizontal structural element with a top flange a concrete form including a bottom member with a cross cleat secured thereto and having one end projecting therefrom, comprising a strap consisting of a wire having a loop at one end thereof adapted to extend around and form a sling for the projecting end of the cleat and having its other end bent laterally at substantially right angles and adapted upon raising of said bottom member under the element to be

brought into overlying relation with the flange, means connected to said other end of the wire for holding the strap in suspended relation with the element, and a separately formed U-shaped member applied to the loop and serving to form a bearing for the cleat.

5. A hanger apparatus for suspending from a horizontal structural element with a top flange a concrete form including a bottom member with a 10 cross cleat secured thereto and having one end projecting therefrom, comprising a strap consisting of a U-shaped wire adapted to extend around and form a sling for the projecting end

of the cleat and having the ends thereof bent laterally at substantially right angles and adapted upon raising of said bottom member under the element to be brought into overlying relation with the flange, a hook connected to 5 said ends of the wire and adapted to hook around the flange of the element and to hold the wire in suspended relation with the element, and a U-shaped element connected to the lower portion of the wire and serving to form a cleat engaging 10 bearing.

EROR HILLBERG.
